UNITED STATES PATENT OFFICE.

CHARLES H. LOW, OF SANDWICH, ILLINOIS, ASSIGNOR OF ONE-HALF TO
J. PHELPS ADAMS, OF SAME PLACE.

DRIVE-CHAIN.

SPECIFICATION forming part of Letters Patent No. 256,014, dated April 4, 1882.

Application filed December 22, 1881. (No model.)

To all whom it may concern:

Be it known that I, CHARLES H. Low, of Sandwich, in the county of De Kalb and State of Illinois, have invented certain new and useful Improvements in Drive-Chains, which are set forth in the following specification, reference being had to the accompanying drawings, in which—

Figure 1 is a plan view of a piece of chain embodying my improvements; Fig. 2, a detail section of the same, on an enlarged scale, taken on the line $x-x$ of Fig. 1, showing two successive link-sections, and in dotted lines one of said link-sections in the position in which it is placed in relation to the coupler when about to be connected with or disconnected from the same; Fig. 3, an end view, on an enlarged scale, of one of the couplers detached; Fig. 4, a detail section of the same, taken on the line $y-y$ of Fig. 3; and Fig. 5, a plan view, on an enlarged scale, of one of the link-sections detached.

My invention relates to drive-chains the links of which are composed of two separable parts.

The invention consists in link-sections having irregular-shaped end bars, combined with couplers having corresponding end openings, as will be hereinafter more fully explained.

In the drawings, A represents one of the link-sections, and B represents the coupler. The link-section is of the form of the half-link which would be formed by bisecting longitudinally a rectangular link. The end bar, a , of this link-section is key-shaped. The coupler B has recesses b , adapted to receive the key-shaped end of the end bar. This coupler is also provided with a recess or chamber, b' , in which the end of the key-shaped end of the end bar of the link-section turns and is locked therein. The recess in the coupler is adapted to receive the end bar of the link-section when in a certain relative position and hold it locked therein when in other relative positions. This construction makes the detachment of the parts possible only under certain conditions, and not liable to occur in any ordinary use of the chain.

In the accompanying drawings I have shown a separate recess for each key-shaped end bar; but this is not necessary, as the end bars could

be received into the same chamber in the coupler.

The operation of my invention is as follows: In constructing a chain from the link-sections 55 A and couplers B the end bar of the link-section is inserted into the end of the coupler by holding the link-section in that position in relation to the coupler which is shown in dotted lines in Fig. 2, where, the lug of the end 60 bar being opposite lug-shaped extensions of the recess b , the end bar easily enters the coupler and penetrates it until the lug is opposite the recess b' ; when there is no obstruction presented to the lug, when the link-section is 65 turned down from the position shown in dotted lines in Fig. 2 to that shown in full lines in the same figure, in which position the link-section is in the plane of the line of draft. As that portion of the recess b where the lug enters is out of the line of draft, it will be obvious that the link-sections cannot become detached from the couplers when the chain is in use. 70

When the end bars closely fit the holes in 75 the couplers it may be necessary, of course, to adjust at the same time both end bars of a given link-section in relation to their respective couplers.

Having thus described my invention, what I 80 claim as new, and desire to secure by Letters Patent, is—

1. A drive-chain composed of rectangular links divided lengthwise, provided with lugs or enlargements on the end bars of the link sections, and couplers provided with end openings corresponding with the end bars and adapted to receive them when in an unusual relative position, whereby these parts may be coupled and uncoupled by bringing them into 90 a position different from their working position, substantially as described.

2. The link-sections having end bars provided with lugs, in combination with short couplers having end openings corresponding 95 therewith, and an interior recess within which the said end bars and lugs may turn freely when coupled, substantially as described.

CHARLES H. LOW.
